UNITED STATES PATENT OFFICE

AUGUST MITCHELL, OF NEW YORK, N. Y., ASSIGNOR TO THE CHASE COMPANIES,
INCORPORATED, OF WATERBURY, CONNECTICUT, A CORPORATION

DESIGN FOR A PORTABLE BATTERY LAMP

Application filed May 28, 1932. Serial No. 43,930. Term of patent 3½ years.

To all whom it may concern:

Be it known that I, AUGUST MITCHELL, a citizen of the United States, residing at New York, in the county of New York and State of New York, have invented a new, original, and ornamental Design for a Portable Battery Lamp, of which the following is a specification, reference being had to the accompanying drawing, forming part thereof.

Fig. 1 is a front view of a portable battery lamp showing my new design;

Fig. 2 is a side view of the same;
Fig. 3 is a plan view of the same; and
Fig. 4 is a perspective view of the same with the bail swung down in a position to serve as a support.

I claim:

The ornamental design for a portable battery lamp as shown and described.

AUGUST MITCHELL.
